COMBUSTION CONTROL

Robert E. Bressler, Oregon, Ill., assignor to Kol-Master Corporation, Oregon, Ill., a corporation of Illinois

Application December 7, 1939, Serial No. 308,004

4 Claims. (Cl. 110—101)

This invention relates to improvements in combustion controls and it consists of the matters hereinafter described and more particularly pointed out in the appended claims.

5 The improved control is especially adapted for use in connection with stokers of the underfeed type, such as are used in connection with the furnaces for heating.

It must be borne in mind that the average 10 owner of a stoker-equipped home knows little, if anything, of how or why a stoker functions automatically. Therefore, the owner is not only incapable of making adjustments thereon but is incapable of meeting any emergency should the 15 stoker stop functioning as intended, as for example should the fire go out. Should the fire go out in the retort of such a stoker, when the usual controlling thermostat still calls for heat, the fuel is continuously fed into the furnace and 20 the result is often disastrous. Under such conditions the furnace usually fills up with fuel causing the fuel door to open so that the fuel spills out on the floor. However should the door fail to open, the result might be that the furnace 25 would be lifted off its setting. If, for any other reason, a great excess of fuel is fed to the retort, the same result would obtain.

One of the objects of the present invention is to provide a combustion control which, if the air 30 being supplied during a burning period is not sufficient in volume for the fuel being supplied, or if the fuel being supplied is more than is necessary for efficient combustion, or if the fire goes out and the fuel feed continues, will stop the stoker completely until the condition that caused the stoppage is rectified.

Another object of the invention is to provide 35 a combustion control whereby it is possible after a stoker stoppage, to use the air supplying means in connection with the restarting of the fire, independently of the fuel feeding means, to support the combustion of the fuel bed until more fuel is necessary therefor and may be fed thereto, after which the stoker will find its balance 40 between the fuel and air supplied and will then function automatically under the control of its associated thermostat.

Also, it is an object of the invention to provide 45 a control of such simplicity that it may be readily manipulated even by an inexperienced stoker user to restart the fire after an "out" period.

Again, it is an object of the invention to provide 50 a combustion control especially advantageous in connection with a bin-fed stoker or a stoker having a large capacity hopper to stop

the stoker completely in case of an "out" fire and thus prevent the continued feeding of the fuel from the bin or hopper and the flooding or overfeed of fuel with attending disastrous results.

The above mentioned objects of the invention, 5 as well as others, together with the advantages thereof will more fully appear as the specification proceeds.

In the drawing:

Fig. 1 is a view in side elevation of a stoker 10 for burning fuel and with which a combustion control embodying one form of the invention may be advantageously employed.

Fig. 2 is a view in elevation of the front end 15 of the apparatus appearing in Fig. 1.

Fig. 3 is a diagrammatic view of the improved control employed in connection with the stoker structure appearing in Figs. 1 and 2.

Referring now in detail to that embodiment of the invention illustrated in the drawing, the 20 stoker with which the improved control is employed includes, as best shown in Figs. 1 and 2, a burner 5, a hopper 6, and a means 7 whereby fuel is fed from the hopper to the burner. Said stoker also includes a blower 8 for supplying the 25 necessary air under pressure, a duct 9 for conveying the air under pressure to the burner and a motor 10 which, in this instance drives both the fuel feeding means and the blower.

The burner 5 comprises a hollow windbox 11 30 in which a retort 12 is located in suitable relation to provide a chamber in said windbox surrounding the retort, said windbox having an air inlet at its front bottom end connected to the duct 9. At the top of the windbox is a dead 35 plate 13 and arranged between the inner margin of the dead plate and the top of the retort are the tuyères 14 whereby air under pressure is admitted from the windbox to the fuel bed for combustion purposes.

The fuel feeding means 7 before mentioned includes a feed tube section 15 between the rear end of the lower portion of the hopper 6 and the fuel inlet opening of the burner and a second tube section 16. The last mentioned section is in axial alignment with the first mentioned one and is arranged between the front end of the lower portion of the hopper 6 and the rear side of an upright casing 17 located in front 50 of the hopper. In the tube sections 15 and 16, which in this instance are disposed in the longitudinal median line of the hopper 6, is located a feed screw 18. Said feed screw includes a shaft 19 and a flight 20 thereon of a diameter approxi- 55

mating that of the inside diameter of the said tube sections 15 and 16.

The feed screw 18 extends from casing 17 through the tube section 16, the bottom of the hopper 6 and through the tube section 15 into the rounded bottom portion of the retort.

A relatively large worm gear 21 is fixed to that end of the shaft 19 of the feed screw 18 arranged in the casing 17 and in the top end of said casing is journaled a transverse shaft 22 that appears in dotted lines in Fig. 2. This shaft carries a worm 23 which meshes with the worm gear 21 fixed to the feed screw shaft as before described. The right hand end of the shaft 22 as appears in Fig. 2 extends outwardly beyond the associated side of the casing 17 and there has fixed to it a plurality or a set of stepped pulleys 24-25 and 26 respectively. These pulleys successively increase in diameter outwardly from the associated side of the casing.

At the top portion of the casing 17 is a forwardly extending shelf 17a (see Figs. 1 and 2) and dependingly supported from the underside thereof, forwardly of the casing 17 is the electric motor 10. This motor includes an armature shaft 28, opposite end portions of which project beyond opposite ends of the motor. The right hand end of said shaft has a plurality or a set of stepped pulleys 29-30 and 31 respectively, fixed thereon and which successively decrease in diameter outwardly from the associated end of the motor. The pulleys in one set are arranged in the planes of the pulleys of the other set and a belt 32 is provided to drive one pulley in one set from an associated pulley in the other set. By changing the belt from one pair of associated pulleys in both sets thereof to another pair of associated pulleys thereof, it is possible to provide a number of different speed ratios of the drive between the motor 10 and the shaft 22. It is of course apparent that this change of speed ratios between said motor and said shaft may be obtained through other means than the sets of pulleys and associated belt. The latter, however, is illustrated and described as substantially the simplest arrangement by which this change in speed ratios may be obtained. Also, it is apparent that should the motor 10 be in operation, the drive for the feed screw 18 may be disconnected therefrom and reconnected thereto by removing and replacing the belt 32.

The left hand end of the armature shaft extends into the blower casing 8 where it has fixed to it a rotor or fan of any desired type but not shown herein. The left hand side of the blower casing, as viewed in Fig. 2 is provided with the usual air inlet opening (not shown).

The air duct 9 connects the discharge side of the blower 8 with the inlet of the windbox 11 and this duct is arranged in a plane below that of the hopper 6 so as to pass beneath the same.

On the top side of the shelf 17a is located a control or pressure switch indicated as a whole by the numeral 33, the construction of which best appears in Fig. 3. It includes a diaphragm casing comprising top and bottom, oppositely facing casing parts 34 and 35 respectively, each having an outwardly extending radial marginal flange. A flexible diaphragm 36 is clamped at its peripheral margin between the marginal flanges of the casing parts 34 and 35. Rigid discs 37 are secured to opposite sides of the diaphragm 36 by means of an axially disposed upwardly extending stem 38 and associated nuts. The stem passes through an axial hole in the top casing

part 35. The bottom of the diaphragm casing is connected to the duct 9 by a tube 39 and whereby substantially the same pressure is present in the casing below the diaphragm 36 as exists in said duct.

The switch 33 also includes a switch casing 40 arranged in spaced relation above the diaphragm casing and on the bottom wall thereof is located a fixed contact 41 (see Fig. 3). 42 indicates a lever that is pivoted at one end in the casing 40 and carries a contact 43 at its other end for a make and break engagement with the fixed contact. A spring 44 is fixed at one end to the casing in the plane of the pivotal connection for the lever, and is fixed at its other end to the lever at a point between its ends. This lever 42 is so arranged that when it is in a position wherein its contact 43 engages the contact 41, the mid portion thereof is substantially engaged by the top end of the stem 38. In the present instance the weight of the diaphragm 36 is intended to be more than the air pressure in the windbox 11 and duct 9 will lift at maximum pressure. Therefore, as shown herein lock nuts 45 are provided on the stem 38 above the diaphragm and a spring 46 surrounds the stem between the diaphragm casing and nuts 45 to assist the diaphragm in lifting the lever 42 to disengage its contact from the contact 41.

When the stem 38 has lifted the lever 42 past the horizontal position, the spring 44 will function to swing said lever up against a stop 47 provided therefor in the casing 40 and to hold the contacts mentioned in the separated condition as appears in full lines in Fig. 3. When the pressure of the air in the duct drops, as will later appear, so that the stem 38 descends to a position permitting the lever 42 to be moved to engage its contact 43 with the contact 41, said lever may be moved into this last mentioned position by the following means.

48 indicates a plunger that is arranged for a sliding movement through the top wall of the casing 40 substantially in line with the stem 38 and in the vertical plane of the lever 42. The top end of this plunger is provided with a head 49 and a spring 50 surrounds that part of the plunger between its head 49 and the top wall of the casing and this spring functions normally to urge the plunger 48 upwardly. When the stem 38 is out of the way, a pressure on the head end of the plunger 48 will depress the lever 42 and swing it through the horizontal plane of its pivoted end when the spring 44 will act to swing the lever into a position wherein its contact 43 engages the contact 41.

In Fig. 3 is illustrated one form of control circuit for use in connection with the apparatus heretofore described. Said circuit includes a temperature responsive device 51 in the nature of a room thermostat 51, a limit control 52, a transformer 53, a relay coil 54 and associated armature 55.

The thermostat 51 is usually located in the room or space being heated and the limit control 52, which is associated with the furnace with which the stoker structure is employed, normally functions as a closed switch. The transformer 53 includes the primary and secondary windings 56 and 57.

58 and 59 indicate the main current conductors leading from a suitable source of electric current supply. The conductor 58 leads into one side of the limit control and a line 60 leads out of the other side of said control to a contact 61.

and with which the armature 55 is associated. A line 62 connects the armature 55 to the lever 42 and a line 63 connects the contact 41 with one side of the motor 10, the other side of said motor being connected to the conductor 59. When the armature 55 is engaged with the contact 61, under the control of the thermostat 51, the motor 10 is energized, assuming of course that the limit control 52 is functioning as a closed switch with- 10 in its operative range. When the armature 55 is out of engagement with the contact 61, the motor 10 is deenergized.

The opposite ends of the primary winding 56 of the transformer 53 are normally connected 15 by lines 58a and 59a to the lines 58 and 59 respectively. One end of the secondary winding of the transformer 53 is connected to one side of the thermostat 51 by a line 64 and the other side of said secondary winding is connected by 20 a line 65 to one side of the coil of the relay 54. The other side of the thermostat is connected by a line 66 to the other side of said coil 54.

A branch line 67 is provided between the lines 62 and 63 and in said branch line is a manually 25 operable, normally open switch 68. A transformer 69 has its primary winding 70 connected to the lines 62 and 63 and has its secondary winding 71 connected to opposite sides of an audible signal 72 which is shown herein as a bell.

Assume that after a standby period, the contacts 41 and 43 are engaged and that the thermostat 51 calls for heat so as to energize the relay coil 54 to attract its armature 55 and engage it with the contact 61. This will close the circuit 30 from the conductor 58, through the limit control 52, line 60 to line 62, lever 42, contacts 43 and 41 to line 63 and through the motor 10 to the conductor 59. As the motor 10 is now energized, it will drive the feed screw 18 to feed fuel to the 35 retort and will drive the blower 8 to provide a volume of air under pressure through the duct 9 to the retort so as to support the combustion of the fuel bed.

The amount of air delivered by the blower ordinarily will be sufficient to burn all the fuel fed by the screw 18 and by reason of the condition of the fuel bed, the pressure of the air in the duct being insufficient to actuate the diaphragm 37 to cause the lever 42 to be moved to its open position. Under ordinary conditions, the stoker will function to deliver fuel and proportioned air to the retort until the thermostat 51 is satisfied as to temperature. At that time, the thermostat will break the circuit to the relay coil 54 so that 40 it becomes deenergized. The armature 55 then moves out of engagement with the contact 61 thus opening the circuit for the motor 10 which becomes deenergized and stops driving the feed screw and the blower.

Assuming that during a period of stoker operation when the thermostat is still calling for heat, some failure occurs so that either a greater amount of fuel is fed to the stoker than the stoker will burn or that the fire goes out. Under 45 either condition just mentioned, the resistance to the passage of air through the fuel bed will cause an increase in windbox pressure and which increase will be felt in the diaphragm casing below the diaphragm by reason of the tube 39. When this pressure becomes excessive, it will 50 cause the diaphragm 36 to flex upwardly so that its associated stem 38 will engage the lever 42 and swing it through the horizontal plane of its pivoted end, after which the spring 44 will swing 55 said lever into the full line position shown in

Fig. 3 so that the contact 43 is disengaged from the contact 41.

This, of course, will open the circuit to the motor which stops, so that no more fuel and air is fed to the burner. When the motor circuit is thus opened, and with the thermostat 51 still calling for heat, the transformer 69 becomes energized to sound the signal 72 but the current load passing through the transformer is not enough to operate the motor. When the signal 10 is thus sounded, the user is notified that the stoker has stopped with the thermostat still calling for heat.

To restart the stoker, a source of combustion is applied to the fuel bed to start it burning again. 15 Either before or after the fuel bed has been thus kindled, the operator removes the belt 32 from the pulleys about which it was trained so as to operatively disconnect the feed screw 18 from the motor 10. Thereafter the operator actuates 20 the manual switch 68 so as to close the circuit for the motor 10 therethrough, and this is independently of the switch 33 as a whole. When the switch 68 is thus closed, no appreciable current passes through the transformer 69 so that 25 the signal 72 stops. When the motor is thus energized, it drives the blower 8 to supply the amount of air which will sustain combustion of the fuel bed, which at this time is relatively high. After the fuel bed has a good burning start, the 30 operator depresses the plunger 48 to throw the lever 42 into a position wherein its contact 43 is engaged with the contact 41.

If at the time that the operator depresses the plunger the fuel bed has not burned down sufficiently, then the excessive pressure in the windbox and below the diaphragm 36 will hold the stem 38 in its "up" position so that it prevents the lever 42 from moving into its circuit closing position. If the fuel bed has burned down sufficiently, it is apparent that the air being fed 40 to the fuel bed meets a reduced resistance so that the pressure in the duct 9, and against the bottom side of the diaphragm, will permit the diaphragm to move towards its normal position so as to cause the stem 38 to move out of its position preventing or barring the movement of the lever. Thus when the operator again depresses the plunger 48, the lever 42 is actuated to engage the contact 43 with the contact 41 and restore 45 the circuit for the motor 10 through the switch 33 as a whole.

Thereafter the operator opens the manual switch 68 and replaces the belt upon the proper pulleys of the sets of pulleys before mentioned. This operation again connects the feed screw 18 50 to the motor 10 so that it functions to feed fuel to the fuel bed on the retort. The stoker thereafter functions under the control of the thermostat as before.

It is apparent that the improved control forms 55 a safety device for the stoker which may never be called into operation for its intended purpose, but which, if occasion should arise, may be readily brought into operation for its intended purpose. The device is especially valuable where the fuel is being fed to the retort from a bin or large hopper, because should the fire go out there is no possibility of the feeding that amount of fuel to the furnace as will discharge through the 60 fire door should the same be pressed open or damage the furnace should the fire door, for some reason, fail to open.

While in describing the invention I have referred in detail to the form, arrangement and 75

construction of parts, as well as the operation thereof, the same is to be considered only in the illustrative sense so that I do not wish to be limited thereto except as may be specifically set forth in the appended claims.

5 I claim as my invention:

1. In combination with a retort for supporting a fuel bed, means for feeding fuel to the retort to provide a fuel bed thereon, means for delivering air to the fuel bed to support combustion thereof and which bed offers a resistance to the passage of air therethrough so that the pressure of said air varies with the depth of the fuel bed, power means, means operable to connect said fuel feeding means to or to disconnect the same from said power means, means for driving said air delivering means from said power means, an electric circuit for said power means including a switch responsive to a relatively high pressure condition of the delivered air for opening said circuit to stop said power means, manually operable means for closing said circuit independently of said switch to restart said power means for driving said air supplying means after said fuel feeding means has been disconnected from said power means, and a second manually operable means for actuating said switch at a lower pressure condition of the delivered air to close said circuit for maintaining said power means in operation after said first mentioned manually operable means has been actuated to open said circuit therethrough.

2. In combination with a retort for supporting a fuel bed, means for feeding fuel to the retort to provide a fuel bed thereon, means for delivering air to the fuel bed to support combustion thereof and which bed offers a resistance to the passage of air therethrough so that the pressure of said air varies with the depth of the fuel bed, power means, means operable to connect said fuel feeding means to or to disconnect the same from said power means, means for driving said air delivering means from said power means, an electric circuit for said power means including a switch responsive to a relatively high pressure condition of the delivered air for opening said circuit to stop said power means, a signal device in said circuit and operative when the circuit has been opened through said switch to indicate this condition of the circuit, manually operable means for closing said circuit independently of said switch to restart said power means for driving said air supplying means, after said fuel feeding means has been disconnected from said power means, and a second manually operable means for actuating said switch at a lower pressure condition of the delivered air to close said circuit for maintaining said power

means in operation after said first mentioned manually operable means has been actuated to open said circuit therethrough.

3. In combination with a retort for supplying a fuel bed, means for feeding fuel to the retort to provide a fuel bed thereon, a blower for delivering air to the fuel bed to support combustion thereof and which bed offers a resistance to the passage of air therethrough so that the pressure of said air varies with the depth of the fuel bed, 10 a motor driving said blower direct, means operable to connect said fuel feeding means to or to disconnect the same from said motor, a circuit for said motor, a switch in and normally holding said circuit in a closed condition, means responsive to a relatively high pressure condition of the air delivered by the blower to actuate said switch to open said circuit and stop said motor, manually operative means for closing said circuit after it has been opened by said switch so as 20 to restart said motor after the fuel feeding means has been disconnected from said motor, and a second manually operable means for actuating said switch at a lower pressure condition of the delivered air for closing said circuit for maintaining said motor in operation after said first mentioned manually operable means has been actuated to open said circuit therethrough.

4. In combination with a retort for supporting a fuel bed, means for feeding fuel to the retort to provide a fuel bed thereon, a blower for delivering air to the fuel bed to support combustion thereof and which bed offers a resistance to the passage of air therethrough so that the pressure of said air varies with the depth of the fuel bed, 35 a motor driving said blower direct, means operable to connect said fuel feeding means to or to disconnect the same from said motor, a circuit for said motor, a switch in and normally holding said circuit in a closed condition, means responsive to a relatively high pressure condition of the air delivered by the blower to actuate said switch to open said circuit and stop said motor, a signal device in said circuit and operable when the circuit has been opened through said switch 40 to indicate this condition of said circuit, manually operable means for closing said circuit after it has been opened by said switch to render said signal device inoperative and to restart said motor after said fuel feeding means has been disconnected from said motor, and a second manually operable means for actuating said switch at a lower pressure condition of the delivered air for closing said switch to maintain said motor in operation after said first mentioned manually operable means has been actuated to open said circuit therethrough.

ROBERT E. BRESSLER.
